London W. C. 2, England

Application January 2, 1942, Serial No. 425,430
In Great Britain November 4, 1940

23 Claims. (Cl. 250—36)

This invention relates to electrical apparatus adapted to operate at high frequencies (and more especially at frequencies corresponding to wavelength in vacuo of less than 1 metre) of the type comprising a pair of conductors arranged side by side and cooperating to form a transmission line along which there are standing electric waves. The conductors may be, for example, a pair of parallel rods or a pair of concentric cylinders.

In such apparatus oscillating voltages may be developed between corresponding points on the conductors that are very much higher than any steady voltage applied to the apparatus; the power of the oscillations that can be generated in the apparatus may then be limited by the passage of a discharge through the air between the conductors or by the formation of a corona on one or both of them. The object of this invention is to increase the limit set to the power by this possibility.

It is well known that a discharge from or a corona on a conductor can be suppressed by surrounding the conductor with a dielectric of a dielectric strength and dielectric constant greater than that of air. Solid and liquid dielectrics of high dielectric strength are undesirable in apparatus of the type specified because the dielectric loss in them is too great. The other alternatives are a vacuum or a gas at a pressure higher than atmospheric. But the use of these dielectrics requires the presence of a sealed envelope around the conductor; the problem then arises of making connection between the conductor inside the envelope and the rest of the apparatus outside without incurring the danger of a discharge or corona. This problem can be solved by arranging matters so that the connecting part is at or near a voltage node of the oscillations, so that the part is exposed only to small oscillating voltages.

According to the invention a high-frequency electric oscillation generator comprises a pair of thermionic valves at least two of the leads to which co-operate to form a transmission line along which there are standing electric waves and wherein at least one of the leads is enclosed throughout the greater part of its length in a sealed envelope, the points where any part of the one lead emerges from the envelope for connection to a part of the associated one of the valves, that is not grounded for high-frequency oscillations, being in the neighborhood of a voltage node of the oscillations.

In accordance with a particular form of the invention, a high-frequency wave-signal translating system comprises a pair of conductors cooperating to provide a resonant transmission line

open at one end and coupled at a given point spaced from the said one end to a wave-signal translating apparatus to develop along the line standing waves of potential having a maximum value limited by the corona discharge between the conductors at the aforesaid open end. The system includes a non-conductive sealed envelope enclosing the open end of at least one of the conductors in a medium at such pressure as substantially to increase the maximum potential at which the corona discharge is initiated between the conductors at the open end of the line, the envelope terminating at one end along the aforesaid one conductor substantially only in the neighborhood of a voltage node of the standing wave developed therealong.

If there is a high vacuum within the envelope there will be little difficulty in securing the necessary dielectric strength. But since some power is always dissipated in the conductors, it may be difficult to cool them sufficiently. Then the sealed envelope may contain compressed gas. Carbon dioxide is a convenient gas; for, in order to avoid the difficulty of sealing off a vessel containing gas at high pressure, the gas may be condensed by cold during the sealing off. (No novelty is claimed for this device per se.) Alternatively, vapours, such as those of carbon tetrachloride, or dichlorodifluoro-methane, which are known to have great dielectric strength, may be used in place of carbon dioxide.

Apparatus of the type specified is often operated at high altitudes where the atmospheric pressure is much less than normal. It may happen then that a corona or discharge occurs only when the apparatus is taken to such altitudes. Then the sealed envelope may be filled with air at normal atmospheric pressure; for in the circumstances of use the gas will be "compressed," i. e., at a pressure higher than that of the surrounding region.

Two embodiments of the invention will now be described by way of example with reference to the accompanying drawing, in which

45 Figure 1 is a sectional diagram of part of a high frequency electric oscillation generator;

Figure 2 is a diagram of the same generator, drawn to a smaller scale, and showing elements not appearing in Figure 1; and

50 Figure 3 is a sectional diagram of an alternative embodiment.

In Figs. 1 and 2 a pair of thermionic valves 1, 1', arranged to operate in push-pull, have external anodes 2, 2'. The anodes are effectively continuous with the copper discs, 3, 3', into holes in which they are set. 4, 4' are the cathode con-

nections emerging at one end of each valve; as shown in Figure 2, these connect to lines 14, 14', each consisting of a pair of concentric conductors insulated from one another. One end of the cathode heating element of valve 1 is connected to the inner conductor of the line 14, while the other end of the heating element and the cathode emitting surface are connected in common to the outer conductor of line 14. The heating element and cathode of valve 1' are similarly connected to the conductor of line 14'. The lines 14, 14' form a parallel transmission line terminated by an adjustable tuning bridge 15. The cathode heater battery is denoted by 16. 5, 5' are terminals to the control grid emerging at the other end of each valve.

The said pair of conductors, being straight parallel rods, which are attached at one end to the grid terminals 5, 5', include straight parallel rods 6, 6'. Standing waves are set up along these conductors and the length of the conductors is so adjusted relative to the wave-length of the oscillations that the ends joined to 5, 5' are at or near a voltage node. Each rod 6, 6' is enclosed within a sealed glass envelope 7, 7' filled with carbon dioxide to a pressure of 2 atmospheres or more.

In order that 6, 6' may be connected to 5, 5', the terminal 5 or 5' is a threaded plug projecting from the bottom of a metal thimble 8, 8' sealed at its edge to the glass 9, 9' of the valve. (This construction is known per se.) The end of 6, 6' is a similar plug 10, 10' brought out similarly from the end of the envelope 7, 7'. 11, 11' are metal connecting pieces, having a threaded hole at each end into which the plugs 5, 5' and 10, 10' are screwed. Exact tuning can be effected by adjusting the lengths of the pieces 11, 11'.

All the parts mentioned are mounted on the metal plate 12, provided with ducts 13 through which a coolant is circulated.

The plate 12 is grounded for high-frequency oscillations and is connected through a battery 17, supplying the anode current for the valves, to each of the cathode lines 14, 14'. Conventional grid-leak resistors 18, 18' are connected in series between the connecting pieces 11, 11', and the junction of the resistors is connected to one terminal of the battery 16. The grids of the valves 1, 1' are thus operated above ground for both high-frequency and unidirectional-bias potentials.

The open-ended transmission line formed by the conductor rods 6, 6', the connecting pieces 11, 11', and the grid leads within the envelopes of the valves 1, 1' thus has an electrical length $\lambda/2$, where λ denotes the wave length of the standing waves in the line; and the part of this line constituted by the enclosed conductor rods 6, 6' has an electrical length substantially $\lambda/4$.

In Figure 3, a thermionic valve 1, constructed and mounted similarly to each of the valves 1, 1' in Figure 1, is associated with a pair of concentric cylindrical conductors 6A and 6B. The inner cylindrical conductor 6A, which is attached by the connecting piece 11 to the grid terminal 5 of the valve, is enclosed within the sealed glass envelope 7, which may be evacuated or charged with any of the gases or vapours hereinbefore specified. The outer cylindrical conductor 6B, which is not enclosed in an envelope, is mounted on the metal plate 12.

What we claim as new is:

1. A high-frequency wave-signal translating system comprising, a pair of conductors co-op-

erating to provide a resonant transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of at least one of said conductors in a medium at such pressure as substantially to increase the maximum potential at which a corona discharge is initiated between said conductors at said open end of said line, said envelope terminating at one end along said one conductor substantially only in the neighborhood of a potential node of the standing wave developed therealong.

2. A high-frequency wave-signal translating system comprising, a pair of parallel conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a pair of non-conductive sealed envelopes enclosing the open ends of individual ones of said conductors in a medium at such pressure as substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

3. A high-frequency wave-signal translating system comprising, a pair of concentric cylindrical conductors co-operating to provide a resonant coaxial transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of the inner one of said conductors in a medium at such pressure as substantially to increase the maximum potential at which a corona discharge is initiated between said conductors at said open end of said line, said envelope terminating at one end along said inner conductor substantially only in the neighborhood of a potential node of the standing wave developed therealong.

4. A high-frequency wave-signal translating system comprising, a pair of conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a nonconductive evacuated envelope enclosing the open end of at least one of said conductors substantially to increase the maximum potential at which a corona discharge is initiated between said conductors at said open end of said line, said envelope terminating at one end along said one conductor substantially only in the neighborhood of a potential node of the standing wave developed therealong.

5. A high-frequency wave-signal translating system comprising, a pair of parallel conductors co-operating to provide a resonant transmission line open at one end and coupled at a given point

spaced from said one end to a wave-signal translating apparatus to develop along said line standing waves of potential having a maximum value limited by the corona discharge between said conductors at said open end, and a pair of nonconductive evacuated envelopes enclosing the open ends of individual ones of said conductors substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

6. A high-frequency wave-signal translating system comprising, a pair of concentric cylindrical conductors co-operating to provide a resonant coaxial transmission line open at one end and coupled at a given point spaced from said one end to a wave-signal translating apparatus to develop along said line standing waves of potential having a maximum value limited by the corona discharge between said conductors at said open end, and a nonconductive evacuated envelope enclosing the open end of the inner one of said conductors substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

7. A high-frequency wave-signal translating system comprising, a pair of conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of at least one of said conductors in a gaseous medium at superatmospheric pressure substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

8. A high-frequency wave-signal translating system comprising, a pair of parallel rod conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a pair of nonconductive sealed envelopes enclosing the open ends of individual ones of said conductors in a gaseous medium at superatmospheric pressure substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

9. A high-frequency wave-signal translating system comprising, a pair of concentric cylindrical conductors co-operating to provide a resonant coaxial transmission line open at one end and coupled at a given point spaced from said one end

to a wave-signal translating apparatus to develop along said line standing waves of potential having a maximum value limited by the corona discharge between said conductors at said open end, and a nonconductive sealed envelope enclosing the open end of the inner one of said conductors in a gaseous medium at superatmospheric pressure substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

10. A high-frequency wave-signal translating system comprising, a pair of conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of at least one of said conductors in a carbon-dioxide gaseous medium at superatmospheric pressure substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

11. A high-frequency wave-signal translating system comprising, a pair of conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of at least one of said conductors in the vapour of a material having great dielectric strength and at such pressure as substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

12. A high-frequency wave-signal translating system comprising, a pair of conductors co-operating to provide a resonant transmission line open at one end and coupled at a given point spaced from said one end to a wave-signal translating apparatus to develop along said line standing waves of potential having a maximum value limited by the corona discharge between said conductors at said open end, and a nonconductive sealed envelope enclosing the open end of at least one of said conductors in carbon-tetrachloride vapour at such pressure as substantially to increase the maximum potential at which a corona discharge is initiated between said conductors at said open end of said line, each of said envelopes terminating at one end along the conductor enclosed thereby substantially only in the neighborhood of a potential node of the standing wave developed therealong.

13. A high-frequency wave-signal translating system adapted to be used at high altitudes comprising, a pair of conductors co-operating to provide a resonant transmission line open at one end and coupled at a given point spaced from

said one end to a wave-signal translating apparatus to develop along said line standing waves of potential having a maximum value limited by the corona discharge between said conductors at said open end, and a nonconductive sealed envelope enclosing the open end of at least one of said conductors in air at normal atmospheric pressure substantially to increase the maximum potential at which a corona discharge is initiated between said conductors at said open end of said line when said system is operated at said high altitudes, said envelope terminating at one end along said one conductor substantially only in the neighborhood of a potential node of the standing wave developed therealong.

14. A high frequency electric oscillation generator comprising a pair of thermionic valves at least two of the leads to which co-operate to form a transmission line along which there are standing electric waves and wherein at least one said lead is enclosed throughout the greater part of its length in a sealed envelope, the points where any part of said one lead emerges from said envelope for connection to a part of the associated one of said valves, that is not grounded for high frequency oscillations, being in the neighborhood of a voltage node of the oscillations.

15. A high frequency electric oscillation generator comprising a pair of thermionic triodes operating in push-pull and whose grid leads are parallel rods which co-operate to form a transmission line along which there are standing electric waves, wherein each said grid lead is enclosed throughout the greater part of its length in a sealed envelope and the whole of the part of each said grid lead lying between said sealed envelope and the envelope of the corresponding thermionic valve is in the neighborhood of a voltage node of the oscillations.

16. A high frequency electric oscillation generator comprising a pair of thermionic triodes operating in push-pull and whose grid leads are parallel rods which co-operate to form a transmission line along which there are standing electric waves, wherein each said grid lead is enclosed throughout the greater part of its length in a sealed envelope containing carbon dioxide at superatmospheric pressure and the whole of the part of each said grid lead lying between said sealed envelope and the envelope of the corresponding thermionic valve is in the neighborhood of a voltage node of the oscillations.

17. A high frequency electric oscillation generator comprising a pair of thermionic triodes operating in push-pull and whose grid leads are parallel rods which co-operate to form a transmission line along which there are standing electric waves, wherein each said grid lead is enclosed throughout the greater part of its length in a sealed envelope containing the vapour of a material having great dielectric strength and the whole of the part of each said grid lead lying between said sealed envelope and the envelope of the corresponding thermionic valve is in the neighbourhood of a voltage node of the oscillations.

18. A high frequency electric oscillation generator comprising a pair of thermionic triodes operating in push-pull and whose grid leads are

parallel rods which co-operate to form an open-ended transmission line of electrical length $\lambda/2$ along which there are standing electrical waves of wavelength λ and wherein each said grid lead is enclosed throughout a length of substantially $\lambda/4$ from the open end of said line in a sealed envelope.

19. A high frequency electric oscillation generator comprising a pair of thermionic triodes operating in push-pull and whose grid leads are parallel rods which co-operate to form an open-ended transmission line of electrical length $\lambda/2$ along which there are standing electrical waves of wavelength λ and wherein each said grid lead is enclosed throughout a length of substantially $\lambda/4$ from the open end of said line in a sealed envelope containing carbon dioxide at superatmospheric pressure.

20. A high frequency electric oscillation generator comprising a pair of thermionic triodes operating in push-pull and whose grid leads are parallel rods which co-operate to form an open-ended transmission line of electrical length $\lambda/2$ along which there are standing electrical waves of wavelength λ and wherein each said grid lead is enclosed throughout a length of substantially $\lambda/4$ from the open end of said line in a sealed envelope containing the vapour of a material of high dielectric strength.

21. A high frequency electric oscillation generator comprising a pair of thermionic triodes operating in push-pull and whose grid leads are parallel rods which co-operate to form a transmission line along which there are standing electric waves, wherein each said grid lead is enclosed throughout the greater part of its length in a sealed envelope and the whole of the part of each said grid lead lying between said sealed envelope and the envelope of the corresponding thermionic valve is in the neighbourhood of a voltage node of the oscillations and wherein the cathode leads of said valves form a parallel line terminated by an adjustable bridge for tuning.

22. A high frequency electric oscillation generator comprising a pair of thermionic triodes operating in push-pull and whose grid leads are parallel rods which co-operate to form an open-ended transmission line of electrical length $\lambda/2$ along which there are standing electrical waves of wavelength λ , wherein each said grid lead is enclosed throughout a length of substantially $\lambda/4$ from the open end of said line in a sealed envelope and wherein the cathode leads of said valves form a parallel line terminated by an adjustable bridge for tuning.

23. A high frequency electric oscillation generator comprising a pair of thermionic triodes operating in push-pull and whose grid leads are parallel rods which co-operate to form an open-ended transmission line of electrical length $\lambda/2$ along which there are standing electrical waves of wavelength λ , wherein each said grid lead is enclosed throughout a length of substantially $\lambda/4$ from the open end of said line in a sealed envelope containing carbon dioxide at superatmospheric pressure and wherein the cathode leads of said valves form a parallel line terminated by an adjustable bridge for tuning.
